UNITED STATES PATENT OFFICE.

GEORGE H. BABCOCK, OF PLAINFIELD, NEW JERSEY.

ROOFING-TILE.

SPECIFICATION forming part of Letters Patent No. 430,365, dated June 17, 1890.

Application filed November 8, 1889. Serial No. 329,680. (No model.)

To all whom it may concern:

Be it known that I, GEORGE H. BABCOCK, a citizen of the United States, residing at Plainfield, in the county of Union and State 5 of New Jersey, have invented certain new and useful Improvements in Roofing-Tiles, of which the following is a specification, reference being had to the accompanying drawings, in which—

10 Figure 1 is a side view, Fig. 2 a face view, and Fig. 3 an end view, of a tile having a flat portion, a raised edge upon one side, and a recurved portion formed mainly of a half-frustum of a cone upon the other side and embodying the several features of my invention. Fig. 4 is a plan view of several tiles, each having a flat surface throughout, arranged as they would be upon the eave of a roof; Fig. 5, an enlarged sectional view, x , 15 Fig. 6, of the form of tile in Fig. 4 and Fig. 20 Fig. 6, a plan view thereof.

My invention relates to clay or other tiles of various forms; and it consists in providing a projection or projections on the under surface of the terminal tiles bearing on the roof, whereby an inclination is imparted corresponding to the inclination of the overlying 25 series of tiles above.

In the drawings, A represents the flat portion of the terminal tile; B, the downward or finishing flange, and C the projection or projections which bear on or near the edge of the roof or substructure D.

The projection C in Figs. 1, 2, and 3 lies 30 parallel with the edge of the roof at a suitable distance from the flange B.

In Figs. 4, 5, and 6 the projections C are employed in plurality, lying at right angles to the edge of the roof, being beveled, as seen 35 in Fig. 5, at a suitable inclination.

In Figs. 1, 2, and 3, E represents the raised edge, and F the recurved portion corresponding with a half-frustum of a cone, and with which the said raised edges E of adjacent tiles interlock. G represents the ornamental projection terminating the recurved portion F, which projection G overhangs the eave of the roof. This ornament may be employed on each consecutive terminal tile or be interspersed at suitable intervals in laying the 45 row, the intervening scrolls F being terminated with any suitable plain finish, if desired. The projection G is not to be confined to the specific design illustrated, but consists, essentially, of any hemispherical or ovoid-shaped terminus or other form giving an ornamental finish.

In Figs. 4, 5, and 6, H represents the upturned flanges of the flat terminal tiles, which interlock with suitable downturned flanges I 50 upon adjacent tiles J of the roof. The projections C in the applications illustrated are made of variable depths, according to the inclinations of the tiles imparted by various modes of interlocking.

What I claim as my invention, and desire to secure by Letters Patent, is—

In combination with interlocking tiles, a terminal tile having a downward flange at its lower edge, and a projection upon its base 55 adapted to support its lower edge in the same relation to the surface upon which they are laid as the corresponding edges of the other tiles of the series.

GEO. H. BABCOCK.
